COMBINATION CONTAINER AND SAFETY GUARD FOR FISHHOOKS

Chester J. Sather, 1215 26th St., Ames, Iowa 50010

Filed Dec. 29, 1969, Ser. No. 20,680

Term of patent 14 years

Int. Cl. D22—08

U.S. Cl. D22—23

FIG. 1

FIG. 8

FIG. 2

FIG. 3

FIG. 4

FIG. 5

FIG. 6

FIG. 7

FIG. 1 is a perspective view of a combination container and safety guard for fishhooks showing my new design,

FIG. 2 is a side view thereof,

FIG. 3 is a top view thereof,

FIG. 4 is a side view opposite to that in FIG. 2,

FIG. 5 is a bottom view thereof,

FIG. 6 is a bottom end view thereof,

FIG. 7 is a top end view thereof, and

FIG. 8 is an elevational view showing this invention relative to a fishing pole and line with said pole and fishing line being in broken lines for illustration only.

I claim:

The ornamental design for a combination container and safety guard for fishhooks, as shown and described.
